UNITED STATES PATENT OFFICE

JOHN J. McBRIDE, OF BAYONNE, NEW JERSEY, ASSIGNOR TO AMERICAN CAR AND FOUNDRY COMPANY, OF NEW YORK, N. Y., A CORPORATION OF NEW JERSEY

METHOD OF ASSEMBLING COMPOSITE HOPPER CARS

Application filed May 9, 1928. Serial No. 276,385.

This invention relates to improvements in composite wood and metal hopper bottom cars, and particularly to the method of assembling same to facilitate repairs thereto and the renewal of such parts as are commonly worn out in service before the remainder of the car structure.

In the accompanying drawings there is illustrated in sectional views a car of the type referred to comprising center sills, a side truss structure of metal and wood, the side truss structure being assembled in such manner as to provide a bottom chord comprising a channel 4 in the position ordinarily occupied by a side sill, a top chord comprising a side plate 10 and an overlapping bulb angle 12 with vertical posts 8 and diagonal braces 9 connected respectively with said top chord and with said bottom chord or channel 4. This general type of trussed side construction, including the top and bottom chord with vertical posts and diagonal braces, is conventional and is merely indicated in the accompanying drawings in such manner as to be well understood by those skilled in the art.

Associated with the top and bottom chords, vertical posts and diagonals and interposed between said top and bottom chords, is a wood sheathing, hereinafter referred to, which occupies the position ordinarily occupied by the metallic sheathing or web plate of the conventional plate girder car side construction, and this sheathing is connected with the posts and diagonals referred to in such manner as to utilize the sheathing with the top and bottom chords, etc., as side girders to carry a considerable portion of the lading in the car. A conventional feature in hopper cars for the purpose of bracing the superstructure consists of gusset plates connected with the sides of the car and with cross ridges, if such cross ridges are present, and also cross ties, which conventionally extend from points somewhat below the top of the side wall entirely across and within the lading portion of the body of the car.

Where such gussets are connected directly to the sheathing and to the vertical body posts, difficulty is encountered in repairing

the cars because of the limited space provided between the outstanding flanges of said gussets and body posts, between which the sheathing is positioned. To facilitate repairs in this type of car is one of the objects of the present invention.

Another object of this invention is to provide an improved method of assembling composite hopper cars. It has been the practice heretofore in assembling composite hopper cars to assemble the steel work of the under-frame and body complete in one shop and then shift the partially completed structure to another shop where the wood work is assembled with the steel parts. This in some cases rendered the application of parts of the wood work, particularly the car sidings, difficult and slow. In constructing cars in accordance with this invention the steel work of body is but partly assembled before the wood work is applied, and after the wood work has been applied to the partly completed steel work the remainder of the steel work is applied.

In the drawings: Figure 1 is a partial central vertical transverse section of a completed composite hopper car having wood sides and hopper end floors;

Fig. 2 is a vertical section taken on the line 2—2 of Fig. 1;

Fig. 3 is a horizontal section taken on the line 3—3 of Fig. 1;

Fig. 4 is a view similar to Fig. 1 but showing the steel work partially assembled and the wood siding applied thereto in accordance with this invention, without the flooring;

Fig. 5 is a section taken on the line 5—5 of Fig. 4;

Fig. 6 is a partial view of the remaining steel parts which have been assembled prior to being applied as a unit to the structure shown in Fig. 4;

Fig. 7 is a side elevation view, partly in section;

Fig. 8 is a longitudinal central sectional view showing construction of the bolster and the connection of the inclined wood floor; and

Fig. 9 is a partial transverse sectional view, the section being taken on the line 9—9 of

Fig. 8 looking in the direction indicated by the arrow.

The car shown in the drawings is a composite hopper car having channel center sills 1 connected by cover plate 2 and channel side sills 4 joined to the center sills 1 by cross bearers 6. To the side sills 4 are secured the side posts 8 and braces 9, which are connected together at their upper ends by a top chord consisting of plate 10 and angle bar 12. The corner posts A are connected together by an end sheet 14 having an angle top chord 16 and an inwardly projecting bottom flange 18. At the center of the car the oppositely disposed hopper slope sheets 19 and 20 extend from side to side of the car and are secured to the center sills 1 and the channels forming parts of the side sills 4 and have their upper edges engaging upon opposite sides of the upper edge of a cross bearer 6 and forming a cross ridge extending from side to side of the car. In the usual method of constructing cars, the parts so far described are riveted together and, in addition, to the upper edges of the cross bearer 6 and hopper slope sheets 19 and 20 at each side of the car gusset plates 22 are permanently secured. The gusset plates 22 have their outer edges extending vertically and are provided with laterally extending flanges 23 and 24 spaced inwardly from the flanges 8^a of the post sufficiently to permit the insertion of the wood siding 26. The flange 23 is shown as formed integral with the gusset plates 22 while the flanges 24 are formed of angles riveted to the gusset plates and having flanges projecting oppositely to the flanges 23. The upper edges of the gusset plates 22 are connected by a body cross tie 28 formed with laterally extending attaching flanges 29 and 30 spaced from the flanges of the post as are the flanges 23 and 24. The car bodies are then completed by bolting the hopper flooring 32 in position and by inserting the siding 26 between the flanges of the gusset plates and posts and securing it in position by bolts 34 engaging in the flanges of the gusset plates and posts.

Extreme difficulty is experienced in inserting the wood siding between the flanges of the gusset plates and posts owing to the unavoidable discrepancies in measurements in the manufacturing processes; therefore, in constructing cars in accordance with this invention, the posts 8 and diagonal braces 9 are secured to the underframe of center and side sills and cross bearer 6 and the plates 10 and angles 12 are connected to the tops of the posts 8 and braces 9; the end posts are connected by the end sheets 14 and angles 16 and the hopper slope sheets 19 and 20 are secured to the cross bearers 6 and sills 1 and 4, but the rivets which usually secure the gusset plates 22 to the cross bearers 6 are not driven, as shown in Fig. 4. The hopper floor-

ing 32 and wood siding 26 are then put in place, the siding 26 being secured in position by being bolted to posts 8 and braces 9 where gusset plates 22 do not occur. The body cross tie 28 and gusset plates 22 are then assembled by themselves, if desired, and applied to the car, the rivets 33 securing the gusset plates to the hopper cross ridge sheets 19 and 20 and cross bearer 6 driven. The bolts 34 are inserted in the flanges of the gusset plates 22, body cross tie 28 and posts 8 and engaging the wood siding. Assembling the car in this manner permits of the wood siding 26 being applied without difficulty as there is nothing in the interior of the car to interfere with the application of the wood siding to the inner sides of the posts 8 and braces 9. It will, of course, be understood that the gusset plates 22 and body cross tie 28 need not be assembled before application and applied as a unit, but may be applied separately after the wood siding 26 has been applied.

Associated with the parts hereinbefore described are hoppers B-C and associated means for developing a complete car body structure such as bolster D, floor supports E, side hopper sheets of metal b, c and the angles E' which underlie the inclined end flooring to assist in supporting the same, said angles E' being riveted permanently to the corner posts A, posts 8, diagonal braces 9, 9^a and the side sill channels 4. Said angles E' extend obliquely downwardly from the corner posts to the side channels 4 and are connected to the floor supports E as best shown in Fig. 8. The transverse supporting members E are connected with both the center and side sills by rivets 44 and brackets F respectively and the side hopper sheets c are connected to the side sills 4 by means of rivets 40, while bolts 41 connect the planking 32 to the inturned flanges 42 of the side hopper sheets and the transverse members E, as best shown in Fig. 9. As is conventional in this type of construction, the bolster D has an obliquely disposed top cover plate D' upon which rests the planking 32, before referred to.

It is to be understood that the drawings herein are for illustrative purposes only and that various changes in the form and proportions of the device may be made within the scope of the appended claims without departing from the spirit of the invention.

What is claimed is:

1. The method of assembling a composite hopper car which comprises assembling the metal parts of the underframe, side and ends of said car, attaching the wood flooring and siding thereto, assembling the gusset plates and cross braces to form a unit and attaching the unit thus formed to the previously connected siding, sides and underframe.
2. The method of assembling a composite

hopper car which comprises assembling the underframe comprising sills and cross bearers, securing the posts and braces to said sills, connecting the posts and braces by the top chord members of the sides, attaching the hopper slope sheets to the sills and cross bearers, attaching the sidings to the side posts and braces, then attaching the gusset plates to the cross bearers, hopper slope sheets, siding and posts and connecting the gusset plates, siding and posts by braces.

3. The method of assembling a composite hopper car which comprises assembling the underframe comprising sills and cross bearers, securing the posts and braces to said sills, connecting the posts and braces by the top chord members of the sides, placing the end sheets in position and securing the same, attaching the hopper slope sheets to the sills and cross bearers, attaching the wood flooring to the end plates and the siding to the side posts and braces, then attaching the gusset plates to the cross bearers, hopper slope sheets, siding and posts and connecting the gusset plates, siding and posts by braces having direct connection to the posts through the siding.

4. Steps in the method of assembling a composite hopper car which comprise assembling an underframe comprising sills and cross bearers, securing body posts to the side sills, securing the wood siding to the inner faces of the posts, securing transversely extending gusset plates to the hopper slope sheets and cross bearer and to the siding and posts and connecting the gusset plates, siding and posts by braces.

5. Steps in the method of assembling a composite hopper car which comprise assembling an underframe comprising sills and cross bearers, securing the hopper slope sheets to the sills and cross bearers, securing body posts to the side sills, securing the wood siding to the inner faces of the posts, connecting gusset plates and braces while detached from the car and applying said gusset plates and braces to the hopper slope sheets and cross bearers and to the posts and siding.

6. Steps in the method of assembling a composite hopper car which comprise assembling the metal parts of an underframe and sides having posts, attaching hopper slope sheets to said underframe, attaching wood siding to the inner faces of the metal parts of the sides and to said posts, connecting gusset plates and cross braces together to form a unit and securing said unit in position in the car body.

In witness whereof I have hereunto set my hand.

JOHN J. McBRIDE.
